United States Patent Office

Des. 228,266
Patented Sept. 4, 1973

228,266

CLOG

Joseph P. Famolare, Jr., Florence, Italy, assignor to
Famolare, Inc., New York, N.Y.

Filed Apr. 12, 1972, Ser. No. 243,553

Term of patent 14 years

Int. Cl. D2—04

U.S. Cl. D2—292

FIG. 1

FIG. 2

FIG. 3

FIG. 4

FIG. 6

FIG. 1 is a perspective view of a clog embodying the design of the present invention;

FIG. 2 is a side elevational view of the clog;

FIG. 3 is a top plan view of the clog;

FIG. 4 is a bottom plan view of the clog;

FIG. 5 is a rear, end elevational view of the clog;

FIG. 6 is a front elevational view of the clog.

I claim:

The ornamental design for a clog, substantially as shown and described.
